ROUTE HOLDER OR SIMILAR ARTICLE

Larry Lee Pierce, Flagview Park 1-A,
Douglasville, Ga. 30134

Filed Feb. 8, 1971, Ser. No. 113,807

Term of patent 14 years

Int. Cl. D20—03

U.S. Cl. D96—9

FIG. 1

FIG. 2

FIG. 3

FIG. 1 is a front elevational view of a route holder embodying the new design;

FIG. 2 is a bottom plan view thereof;

FIG. 3 is a left end elevational view thereof; and

FIG. 4 is a right end elevational view thereof.

I claim:

The ornamental design for a route holder, substantially as shown.
